UNITED STATES PATENT OFFICE

134,612

DESIGN FOR A BEATER

Mark Maynard, Glendale, Calif.

Application October 10, 1939, Serial No. 87,611

Term of patent 14 years

To all whom it may concern:

Be it known that I, Mark Maynard, a citizen of the United States, residing at Glendale, in the county of Los Angeles and State of California, have invented a new, original, and ornamental Design for a Beater, of which the following is a specification, reference being had to the accompanying drawing, forming a part thereof.

I claim:

The ornamental design for a beater, substantially as shown.

MARK MAYNARD.
